SPREADER FOR CLOTHES LINE OF THE TWISTED TYPE

Dennis E. Tiberis, Rehoboth, Mass., assignor to Dennan Manufacturing Company, Providence, R.I., a corporation of Rhode Island

Application November 1, 1954, Serial No. 466,093

5 Claims. (Cl. 211—119.13)

This invention relates to clothes lines, particularly 15 twisted clothes lines which require no pins, and relates more especially to spreaders for use with such twisted clothes lines.

It has long been proposed to dispense with the need 20 for clothes pins by using a twisted clothes line and a spreader. Such lines, although obviously desirable, have not gone into widespread use. In order to securely hold the clothes the twisted line must be under high tension, thus requiring the use of metal wire, which has a tendency to rust. Even if galvanized, the wash will be stained 25 with a gray stain caused by the formation of zinc oxide. This formation also increases the friction and the force needed to relatively move the twisted line and its spreader. The spreader has also been made of metal, thus introducing not only the problem of rust but also the problem of friction, yet at the same time lubrication is 30 virtually impossible because of staining of the clothes. Moreover, exposed metal for the wire or spreader or both is cold to the touch in winter, and tends to freeze to the hand of the housewife.

The primary object of the present invention is to generally improve twisted clothes lines, and more particularly 35 the spreader used with the same. A more particular object is to overcome the difficulties outlined above. For this purpose I have improved both the twisted line itself and also the spreader, but the twisted line is not claimed herein, it being more fully disclosed and claimed in my copending application, Serial No. 465,870, filed concurrently herewith.

To accomplish the foregoing general objects, and other more specific objects which will hereinafter appear, my invention resides in the spreader elements, and their relation one to another, as are hereinafter more particularly described in the following specification. The 45 specification is accompanied by drawings, in which:

Fig. 1 is a fragmentary elevation showing how a twisted line is spread by means of a spreader in order to receive the clothing to be dried;

Fig. 2 is a front elevation of one form of spreader embodying features of my invention;

Fig. 3 is a front elevation of the rotatable core of the spreader;

Fig. 4 is a section taken approximately in the plane of the line 4—4 of Fig. 2;

Fig. 5 is a partially sectioned front elevation of a modified form of spreader of somewhat more complex construction using ball bearings and also using contacting rollers;

Fig. 6 is a transverse section taken approximately in the plane of the line 6—6 of Fig. 5;

Fig. 7 is an exploded view based on Fig. 6 and explanatory of how the parts are assembled;

Fig. 8 is a partially cut away front elevation showing another form of the invention utilizing contacting rollers, and which may be applied to an already secured line;

2

Fig. 9 is a transverse section taken approximately in the plane of the line 9—9 of Fig. 8;

Fig. 10 is a partially cut away front elevation showing a modification of the invention somewhat like that 5 shown in Fig. 5 but through which a twisted line may be passed and later spread;

Fig. 11 is a partially cut away front elevation of a modified form of the invention in which spaced rollers have trunnions and do not run in contact;

10 Fig. 12 is a fragmentary transverse section through the core at one of the rollers;

Fig. 13 is a partially cut away front elevation showing still another form of the invention in which self-lubricating pellets are employed;

Fig. 14 is a fragmentary section taken through the core at one of the pellets; and

Fig. 15 is a plan view of one of the pellets.

Referring to the drawing, and more particularly to Fig. 1, I there show a twisted clothes line made up of strands 12 and 14. These securely hold the corner 16 and will hold the corner 18 of a piece of wash 20. The wires are spread by means of a spreader 22 to receive the wash. It will be understood that if the line is fixedly secured between posts near ground level, the spreader is moved by walking it along the line as the wash is hung or removed. As shown in Fig. 1 it is being moved to the right to hang the wash, and to the left to remove the wash. If the line is an endless line supported around pulleys, the spreader is secured to one of the pulleys, and the line is moved relative to the spreader, instead of vice versa. This is shown in my companion application Serial No. 465,870 mentioned above.

Referring now to Figs. 2, 3 and 4, the spreader there shown comprises a ring 24, and a circular core 26 which is freely rotatably mounted within the ring 24. The core has spaced apertures 28 and 30 which pass through the core in the direction of the axis of the spreader, and which receive the strands of the twisted line. The ring 24 and the core 26 are made of a weather-proof plastic, and the strand bearing parts 28 and 30 are preferably made of a self-lubricating plastic such as nylon or Teflon. The particular form of spreader here shown is comparatively small and simple in structure, and the strand bearing parts 28 and 30 are integral with the core 26, so that the entire core may be made of the self-lubricating plastic. This is of added advantage in making it easier for the core to rotate in contact with the ring 24, the latter being made of a weather-proof plastic such as acetate.

50 From the drawing it will be seen that the core 26 may be molded in one piece. The ring 24 is preferably molded in two pieces which separate on a parting plane 32 (Fig. 4). The two pieces are secured together in edge-to-edge relation, as by welding or cementing or the like, or by means of rivets such as those shown at 34, or both.

The term welding is used for convenience to mean cohering the parts by a solvent or by heat. When the two halves of the ring 24 are secured together they form an internal peripheral groove 36 which is dimensioned to receive the outer periphery of the core 26. The outside periphery of ring 24 may be grooved or made concave, as shown at 38 (Fig. 4), to facilitate holding and moving the same along the line.

65 As so far described it would necessary to string the separated ends of the line through the apertures 28 and 30 before securing the line between poles or the like. In accordance with a feature of the present invention the spreader may be applied to a twisted line which has already been secured at both ends. For this purpose the ring 24 is transversely slotted as indicated at 40, and this slot is dimensioned to pass a strand of the line, and

thus to pass the entire line. The core 26 is notched at diametrically opposite points, as indicated at 42 and 44 in Fig. 3, instead of having simple round holes at 28 and 30. Differently expressed, the core 26 is provided with notches at its periphery which notches lead to and afford access to the apertures 28 and 30.

On reflection it will be evident that the spreader may be applied to an already closed line by simply passing one strand through slot 40 into aperture 28, and then rotating the core for a half turn, thus bringing the other aperture 30 into registration with the slot 40, at which time the other strand is passed into aperture 30. The spreader is then ready for use. There is no danger of the strands accidentally escaping through the slot 40 because the strands are under high tension, and pull toward the center of the spreader. However, the spreader can be intentionally removed from the line by reversing the process for applying the spreader to the line previously described.

Referring now to Figs. 8 and 9 of the drawing, I there show a spreader which is larger in dimension, and improved by the addition of anti-friction rollers 50 and 52 to act as the strand bearing parts of the core. The rotatable core 54 is pocketed or hollowed to rotatably receive the roller 50 and the roller 52. These rollers are so located that the top of roller 50 comes partway into the passage 56 for strand 58, and similarly the bottom of roller 52 comes partway into the passage 60 for strand 62. Thus the strands 58 and 62 run on rollers 50 and 52, with consequent reduction in friction. The rollers 50 and 52 are superposed and have parallel axes disposed transversely of the spreader axis.

As so far described the rollers 50 and 52 might be vertically spaced from one another, the said rollers being located in separate pockets. However, I prefer to give the rollers a diameter so large that they run directly in contact with one another, as is clearly shown in Figs. 8 and 9. It will be understood that this is a rolling contact, for the friction of the strands 58 and 62 would anyway cause the rollers to rotate in opposite directions at equal speeds, and thus the rollers are in direct rolling and anti-friction contact when the spreader and line are relatively moved.

For the present purpose the core 54 is molded in two parts which meet on a parting plane 64 (Fig. 9). The parts may be secured together by welding or cementing, or by the use of rivets 66 (Fig. 8), or both, and when secured together provide a pocket in which the rollers 50 and 52 are rotatably carried. Similarly the outer ring 68 is molded of two parts which separate on plane 64 (Fig. 9) and which are secured together by welding or cementing, or by means of rivets 70 (Fig. 8), or both. When the parts of ring 68 are secured together they form an internal channel which rotatably receives the periphery of core 54.

The ring 68 is preferably made of a dimensionally stable and weather-proof plastic such as acetate, acetate butyrate or Lucite (acrylic resin). The core 54 is preferably made of a self-lubricating plastic such as nylon or Teflon, thus tending to insure free rotation of the core in the ring, as well as free rotation of the rollers in the core. The rollers are preferably made of nylon. It will be understood that by reversing the interfit of the core and ring, or, in other words, by providing the ring 68 with an internal bead, and providing the core with an external channel, it would be possible to mold the ring 68 in one piece. Differently expressed, the molding of the core 54 in two pieces then would serve two purposes, first to receive the rollers 50 and 52, and second to help assemble the core within the ring.

As so far described the passages 56 and 60 might be round apertures through which the separated ends of the strands would be separately passed. However, the spreader may be arranged so that it can be added to an

already secured line, just as was described in connection with Fig. 2. Specifically, the ring 68 may be slotted at 72 to pass a strand of the line, and the core 54 may be notched at diametrically opposite points with notches 55 which lead to the apertures 56 and 60. Thus one strand may be passed through slot 72 into aperture 56 and in contact with roller 50, whereupon the core 54 may be turned a half turn to permit the other strand to be passed through slot 72 and into aperture 60 in contact with the roller 52. The strands then bear against the rollers, and urge the rollers toward one another because of the constant tendency of the twisted wire to close when spread.

The core may be rotated in the ring with the assistance of ball bearings. One form of spreader utilizing ball bearings and rollers is shown in Figs. 5, 6 and 7 of the drawing. Referring to those figures, the spreader comprises, as before, a ring 74 and a circular core 76 freely rotatably mounted within the ring 74. The core 76 has spaced apertures 78 and 80 passing through the core in the direction of the axis of the spreader in order to receive the strands 82 and 84 of a twisted line. In the present case, however, the inner periphery of ring 74 is grooved at 86 (Fig. 6) to form a ball bearing raceway, and the outer periphery of core 76 is grooved at 88 to form a ball bearing raceway. Ball bearings 90 are received in and nearly fill the raceways 86 and 88, thus providing an antifriction bearing between the ring and core. The ring 74, the core 76, and the balls 90 are preferably all made of plastics material.

As before the core 76 may be molded in two parts, separable on a vertical plane 92 (Fig. 6) and secured together by welding or cementing, or by means of rivets 94, or both. The ring 74 also may be made of two parts separating on the plane 92, and secured together by welding or cementing, or by means of rivets 96, or both. However, it is not essential to separate both the core and the ring in order to place the balls 90, and it is sufficient to split one or the other if no rollers are used.

The particular spreader here shown is equipped with anti-friction rollers 98 and 100 which act as the strand bearing surfaces of the core, and which preferably run in rolling contact with one another, as was previously described in connection with Figs. 8 and 9. The rollers may be received in a pocket which just fits them, and it is not necessary to provide a pin or axle for each roller, nor to provide integral projecting trunnions. However, it is necessary to split the core 76, that is to mold it in two parts, and when this is done it is not necessary to mold the outer ring 74 in two parts, at least insofar as assembly is concerned, although it still may be desirable to mold the ring in two parts as here shown for ease of mold design and in order to avoid the need for movable cores. The ring 74 and the core 76 may be molded out of a dimensionally stable weather-proof plastic such as acetate or acetate butyrate. The balls 90 may be made of Lucite or nylon. The rollers 98 and 100 may be molded out of nylon.

It will be noted that the ball bearing form of spreader shown in Figs. 5-7 is not provided with a slot and notches to permit application of the spreader to an already secured line. The reason for this is that the ball bearing action would not be smooth or satisfactory if the balls had to run past the slots. The apertures 78 and 80 in Fig. 5 are accordingly closed apertures through which the ends of the line must be separately passed.

In Fig. 10 I show a modification of the spreader through which the line must be passed, but without requiring spreading of the ends. Specifically, the spreader of Fig. 10 is like the spreader of Fig. 5 in comprising a core 102 which turns in a ring 104 by means of ball bearings 106. The core 102 has diametrically disposed spaced apertures 108 and 110, but these apertures are connected by a curved passage 112. Differently expressed, the core 102 is cut away or hollowed on one side

of apertures 108 and 110 by means of a curved passage 112 which connects the outermost portions of the apertures, thus leaving the retainer points 114 and 116. On reflection it will be evident that a free end of the twisted line may be passed through any portion, usually the center portion, of the curved passage 112. At some later time, and even after the line has been secured between posts or around pulleys, the strands may be separated at the passage 112 until one strand is received in aperture 108 and the other strand is received in aperture 110. The strands then remain in the apertures because of their tendency to close toward the center of the spreader. If desired the core 102 may be provided with strand bearing rollers 118 and 120, just as was described in connection with Fig. 5.

The strand bearing rollers have been devoid of bearing pins or trunnions, and have rolled in contact with one another. I consider this to be a preferred construction, but it is not essential, and strand bearing rollers may be provided which are separated from one another, as shown in Figs. 11 and 12 of the drawing. In those figures it will be seen that core 122 rotates within ring 124 on ball bearings 126. The core has apertures 128 and 130 for the strands of the line. A roller 132 is disposed with its top in aperture 128, and a roller 134 is disposed with its bottom in aperture 130. The rollers 132 and 134 may be formed with integral trunnions 136, and these are received in bearings formed in the core. Instead of making the rollers with integral trunnions, a pin may be passed through each roller. This pin may be made of rust-proof metal or of plastics, but I consider the use of integral trunnions preferable. As before the ring and the core may be made of a dimensionally stable weather-proof plastic; the balls may be made of Lucite or nylon; and the rollers may be made of nylon.

It is possible to provide the core with strand bearing surfaces made of a self-lubricating plastic, without using rollers and yet without making the entire core out of a self-lubricating plastic. Such a construction is shown in Figs. 13, 14 and 15 in which the core 140 rotates within ring 142 on balls 144. The core 140 has apertures 146 and 148 for the strands of the line. An insert or pellet 150 is so disposed as to occupy the lower part of passage 146, and similarly a pellet 152 is so disposed as to occupy the upper part of passage 148. These pellets preferably have convex surfaces in the apertures, and are preferably made of a self-lubricating plastic such as nylon or Teflon. In the particular case here shown the pellets are circular, as will be seen in Fig. 15, and they are seated in mating recesses formed inside the core 140, the latter preferably being molded in two pieces secured together by welding or cementing or/and by rivets, all as previously described.

The twisted line 12, 14 shown in Fig. 1 has not yet been described in detail, but each strand is preferably a high carbon, high tensile steel wire coated with a plastic coating. In a specific case the steel wire is 0.063" in diameter and has a tensile strength of 315,000 p.s.i. The plastic coating is a polyvinyl chloride resin having a thickness of 0.0125". The lay of the twist when using such strands is preferably 4½", and may be in a range from 4" to 5½". A pitch that is much shorter, say 3", will unduly impede the relative movement of the line and spreader, and a pitch that is much longer, say 6½", will not grip the wash with adequate force to hold under heavy load or high wind.

This coated line has the advantage that it is clean, readily washable, and rust-proof and corrosion-proof. It grips the wash more tightly, yet is softer and less injurious to delicate clothing. Because of the plastics coating it does not freeze to the hands of the housewife, nor to the spreader, nor to pulleys when pulleys are used.

In respect to the spreaders, the ring is preferably made of any dimensionally stable and weather-resistant plastic including acetate and acetate butyrate or Lucite (acrylic resin). It could also be made of nylon or Teflon, ex-

cept that these plastics would be too costly. The core, in those forms of the invention which do not have ball bearings is preferably made of a self-lubricating plastic such as nylon or Teflon. In those forms which do have ball bearings the core may be made of any dimensionally stable weather-resistant plastic such as acetate or acetate butyrate. The rollers in those forms utilizing rollers are preferably made of nylon which is both self-lubricating and hard. Teflon is self-lubricating but does not wear as well as nylon. The balls are preferably made of a hard plastic. They may be made of Lucite. Balls made of nylon would be self-lubricating but more costly. The balls may be made of other plastics, say acetate butyrate, if molded in a hard flow, in order to produce a ball of sufficient hardness.

The plastics spreaders, here disclosed are of particular advantage when used with the described plastics coated wire, but their use is not limited to such wire. The wire is not claimed herein, it being claimed in my aforesaid companion application, Serial No. 465,870.

It is believed that the construction and method of assembly and use of my improved spreaders, as well as the advantages thereof, will be apparent from the foregoing detailed description. It will also be apparent that while I have shown and described my improved spreader in several preferred forms, changes may be made in the structures shown without departing from the scope of the invention, as sought to be defined in the following claims.

I claim:

1. A spreader for a clothes line of the twisted type, comprising a ring, and a circular core freely rotatably mounted within the ring, said core having spaced apertures passing through the core in the direction of the axis of the spreader to receive the strands of the twisted line, said ring being transversely slotted at one point with a slot adapted to pass a strand of the line, and said core being notched at diametrically opposite points to provide the aforesaid apertures, whereby the spreader may be applied to a twisted line which has already been secured at both ends.

2. A spreader for a clothes line of the twisted type, comprising a ring, and a circular core freely rotatably mounted within the ring, said core having spaced apertures passing through the core in the direction of the axis of the spreader to receive the strands of the twisted line, said ring being transversely slotted at one point with a slot adapted to pass a strand of the line, and said core being notched at diametrically opposite points to provide access to the aforesaid apertures, whereby the spreader may be applied to a twisted line which has already been secured at both ends, said ring being made of a weatherproof plastic, and the core being made of nylon, Teflon or like self-lubricating plastic.

3. A spreader for a clothes line of the twisted type, comprising a ring, a circular core freely rotatably mounted within the ring, said core having spaced apertures passing through the core in the direction of the axis of the spreader to receive the strands of the twisted line, said ring being transversely slotted at one point with a slot adapted to pass a strand of the line, and said core being notched at diametrically opposite points to provide access to the aforesaid apertures, whereby the spreader may be applied to a twisted line which has already been secured at both ends, and a pair of superposed rollers having parallel axes disposed transversely of the spreader axis at said apertures to act as the strand bearing parts of the core.

4. A spreader for a clothes line of the twisted type, comprising a ring, a circular core freely rotatably mounted within the ring, said core having spaced apertures passing through the core in the direction of the axis of the spreader to receive the strands of the twisted line, said ring being transversely slotted at one point with a slot adapted to pass a strand of the line, and said

core being notched at diametrically opposite points to provide access to the aforesaid apertures, whereby the spreader may be applied to a twisted line which has already been secured at both ends, and a pair of superposed rollers having parallel axes disposed transversely of the spreader axis at said apertures to act as the strand bearing parts of the core, said rollers having a diameter such that they run in rolling contact against one another, and said core being pocketed to rotatably receive said pair of contacting rollers.

5. A spreader for a clothes line of the twisted type, comprising a ring, a circular core freely rotatably mounted within the ring, said core having spaced apertures passing through the core in the direction of the axis of the spreader to receive the strands of the twisted line, said ring being transversely slotted at one point with a slot adapted to pass a strand of the line, and said core being notched at diametrically opposite points to provide access to the aforesaid apertures, whereby the spreader may be applied to a twisted line which has already been secured at both ends, and a pair of superposed rollers having parallel axes disposed transversely of the spreader axis at said apertures to act as the strand bearing parts

of the core, said rollers having a diameter such that they run in rolling contact against one another, and said core being pocketed to rotatably receive said pair of contacting rollers, said ring and core and rollers all being made of plastics materials.
